UNITED STATES PATENT OFFICE.

MICHAEL A. FOSTER, OF ST. LOUIS, MISSOURI.

CARBURETOR.

SPECIFICATION forming part of Letters Patent No. 377,607, dated February 7, 1888.

Application filed March 18, 1887. Serial No. 231,399. (No model.)

To all whom it may concern:

Be it known that I, MICHAEL A. FOSTER, of the city of St. Louis, in the State of Missouri, have invented a certain new and useful Improvement in Carburetors, of which the following is a full, clear, and exact description, reference being had to the accompanying drawings, forming part of this specification, and in which—

Figure I is a side elevation of my improved generator, showing part of the casing in vertical section. Fig. II is a side elevation looking in the direction of the arrow in Fig. I. Figs. III and IV are side elevations taken from different positions. Fig. V is a vertical longitudinal section taken on line V V, Fig. II, the gasometer being shown raised in dotted lines. Fig. VI is a horizontal transverse section taken on line VI VI, Fig. V, part of the wire-gauze being broken away. Fig. VII is a similar view taken on line VII VII, Fig. V. Fig. VIII is an enlarged perspective view of the brake and the device for adjusting it. Fig. IX is an enlarged detail view, to be hereinafter described.

My invention relates to an apparatus for carbureting air by forcing a current thereof through a body of oil; and my invention consists in features of novelty hereinafter more fully described, and pointed out in the claims.

Referring to the drawings, 1 represents a gasometer fitting in a water-chamber, 2, formed by cups or tanks 3 4, having a bottom, 5, but being open at top. The gasometer is guided and held from horizontal movement, but permitted to move vertically, by slotted arms 6, secured to the top of the tanks 3 4, in which fit projections 7 on the gasometer. The gasometer is raised by means of air forced into the tank 3 by means of a bellows, 8, provided with an inlet-valve, 9, communicating with the outer air, and a valve, 10, communicating, through a pipe, 11, with the upper part of the tank 3. The pipe 11 is provided at its upper end with a check-valve, 12, to prevent the escape of air through the pipe. The bellows is operated by a crank, 13, to which it is connected by a pitman, 14, and a fulcrumed rod, 90. (See Figs. II, V.) The crank 13 is secured to a shaft, 15, journaled in a frame, 16, and to which is secured a pinion, 17, that meshes into a wheel, 18, partly broken away

to show drum 20, on a shaft, 19, journaled in the frame 16. On the shaft 19 is a drum, 20, around which is wound one end of a cord, 55 rope, or cable, 21, to the other end of which is secured a weight, 22, the cable preferably passing under pulleys 23 and over a pulley, 24, and the extreme end of the cable being preferably secured to a fixed object, 25, as 60 shown in Fig. III. It will be seen that as the weight falls the bellows will be operated through means of the described connection. The gearing is preferably provided with a fly-wheel, 26, on a shaft, 27, geared into the pinion 17, the object of the fly-wheel being to avoid dead-centers. The shaft of the fly-wheel is journaled in the frame 16, the frame being secured to the tank 4 by screws or bolts 28.

The air that is forced into the tank 3 by the bellows escapes through a pipe, 29, within the tank into a pipe, 30, with which the pipe 29 communicates at 31. The pipe 30 is formed into several coils at one side of the tank 4, and the coils are inclosed by a casing, 32, open 65 at bottom and provided with a neck or chimney, 33, on top. The pipe 30 is provided with a valve, 34, to regulate the passage of the air, which is indicated by featherless arrows in Fig. V. The lower end of the pipe communicates with a horizontal bent perforated pipe, 35, in the bottom of an oil-tank, 36, supported 70 on legs 37, provided with adjustable feet 38, by which the apparatus may be made to set level on uneven surfaces. (See Fig. V.) The air 75 escaping through the perforations in the pipe 35, as shown by the arrows in Fig. V, passes up through the oil in the tank 36, being diffused by a perforated plate, 39, and a wire-gauze plate, 40, located within the tank. The carbureted air escapes from the tank 36 through 80 a main pipe, 41, provided with a funnel, 42, located at the top of the tank. (See Fig. V, the passage of the gas being shown by full arrows.) The pipe 41 is provided with one or 85 more valves, 43, and with this pipe communicate branch pipes (not shown) leading to the respective burners that receive their supply 90 from the apparatus.

I have shown the pipe 41 tapped by a bifurcated pipe, 44, on one arm of which is a testing-burner, 45, and on the other arm of which is a burner, 46, for heating the air in the pipe 95 30 within the casing 32, the heat passing out

through the chimney 33. The air is thus heated to improve its capacity for taking up carbureted hydrogen when passing through the oil.

5 As the air escapes from the tank 3, the gasometer falls, (the mechanism that lifts the gasometer by working the bellows and forcing the air into the tank 3, as stated, being automatically stopped,) and as the gasometer reaches 10 its lower position the bellows is started again automatically. This stopping and starting of the mechanism for operating the bellows is effected as follows: Supposing the gasometer to be elevated to its highest position, as shown 15 by dotted lines in Fig. V, the mechanism is stopped by a brake-shoe, 50, brought against a wheel or drum, 51, on the shaft 27 of the fly-wheel, by an arm, 52, on the gasometer coming against a projection, 53, on the upper 20 end of a bar or plate, 54, the bar being connected at its lower end by a link, 55, to a crank, 56, on a rock-shaft, 57, to which the shoe is secured. The mechanism that operates the bellows is thus automatically stopped 25 by the gasometer when the latter reaches its highest position. As the gasometer reaches its lower position, the arm 52 comes against a projection or shoulder, 58, on the lower end of the bar or plate 54, and by moving the 30 plate downward rocks the shoe 50 away from the drum or wheel 51, and the mechanism starts up again and works the bellows, as described, raising the gasometer again.

For the purpose of causing the arm 52 to 35 operate sooner or later on the bar 54, I make the latter adjustable in length by forming it in two pieces connected by a bolt or rod, 59, having a right and left thread. By turning this bolt in the proper direction it will be seen that 40 the bar will be shortened or lengthened and the shoulders 53 and 58 brought nearer together or moved farther apart. The bar is held in place by keepers or straps 60, securing it to a fixed plate, 61, made fast to the tanks 45 34. As the shoe 50 becomes worn, it may be set up by a wedge, 62, located behind it, and adjusted by nuts 63 on a stem, 64, of the shoe, the nuts being respectively above and below an arm, 65, on the shaft 57, and through which 50 the stem 64 passes.

The oil is poured into the tank 36 through a pipe, 80, having a filling-cup, 81, and a valve, 82. The pipe communicates with the tank at 55 83 and 84, and is provided with a valve, 85, at its lower end, by which the oil may be drawn out of the tank, if desired.

The bottom of the tank may be provided with a removable plate, 88, bolted in place, and closing a hand-hole, 89, through means of 60 which the tank may be cleaned.

Instead of the apparatus being supported on feet it may be suspended by means of a spider, 67, and rope or cable 68. (See Fig. IX.) The spider is formed upon the upper ends of the 65 slotted arms 6.

The gasometer may be provided with a pipe, 70, having a valve, 71, and branches 72 at top

to allow oil to be poured into the tank 3, if desired, to in a measure load the air with gas at this point.

The pipes 30 and 41 may be provided with escape-valves 75, if desired.

The tanks 3 4 may be connected to the tank 36 by arms 100.

101 represents a valve for drawing the water 75 from chamber 2.

The tank 4 is provided with a flange, 105, into which water is poured to fill the chamber 2, the water passing through perforations 106 in the tank above the flange. (See Fig. V.) 80

If the gas is too rich, it may be weakened by air entering the pipe 41 through a pipe, 107, connecting the pipe 41 to the air-pipe 30. The pipe 107 is provided with a valve, 108.

The pipe 30 may be provided with a check- 85 valve, 109, to prevent the return of the air.

115 represents arms or brackets formed upon or secured to the top of the tank 36, and through which the pipes 30 and 41 pass, and by which the pipes are held firmly in vertical position. 9c

I claim as my invention—

1. In a carburetor, the combination, with an air-tank, an oil-tank, and a pipe for supplying oil to the air-tank, of an inlet-pipe and an outlet-pipe communicating with the air-tank, 95 said outlet-pipe also communicating with the oil-tank, and a carbureted-air pipe leading from the oil-tank, as and for the purposes set forth.

2. The combination, in a carburetor, with an air-tank, an oil-tank, a pipe connecting the air-tank with the oil-tank, a pipe leading from the oil-tank, and a suitable air-supply for the air-tank, of a pipe for supplying oil to the air-tank, and a pipe provided with suitable cocks 105 connecting the inlet and outlet pipes of the oil-tank, for the purposes set forth.

3. The combination, with a carburetor having air-supplying mechanism, substantially as herein described, of an automatic braking 110 mechanism, which consists in a brake-shoe, 50, mounted on the shaft 57, a crank, 56, vertical shouldered plate 54, and a projection on the gasometer for engaging the shouldered plate and applying the brakes to the driving mech- 115 anism, as shown and described.

4. In combination with a carburetor made substantially as herein shown and described, mechanism for governing the operation of the air-supply bellows, which consists in a weighted 120 cord, a winding-drum, and intermediate driving-gear, a brake, substantially as described, operated by a projection on the gasometer engaging an adjustable shouldered plate connected to a crank on the brake-shaft, said 125 shouldered plate consisting of the parts 53 58 and adjusting-screw 59, as set forth.

5. In a carburetor, substantially as herein described, the combination, with the mechanism for operating the air-supply, of a brake 130 bearing against a wheel in said mechanism, said brake consisting of a shoe, 50, mounted on shaft 57, a wedge, 62, an arm, 65, on the shaft, a set-screw in the end of the arm bear-

ing upon the wedge, a crank on the shaft, and connected to the crank a rod which is controlled by the gasometer.

6. The combination, with the air-tank and 5 oil-tank, of a pipe, 30, connecting the two tanks, a bellows, 8, supported by a pipe, 11, projecting from the air-tank and making air-connection between the bellows and said tank, perforated plate 39 in the oil-tank, wire-gauze

40 above plate 39, and an outlet, 41, for carbureted air, the said pipe 30 terminating in the perforated coil beneath the plate 39, as and for the purpose set forth.

MICHAEL A. FOSTER.
